[57] CLAIM

The ornamental design for a mounting plate for digger
fingers for a trenching machine, substantially as shown.

DESCRIPTION

FIG. 1 is a front elevational view of a mounting plate
for digger fingers for a trenching machine, showing my
new design;

FIG. 2 is a top plan view thereof;

FIG. 3 is an elevational view of one end thereof;

FIG. 4 is a bottom plan view thereof;

FIG. 5 is a rear elevational view thereof; and

FIG. 6 is an elevational view taken from the end oppo-
site that shown in FIG. 3.
